~~John Francis Chapman~~
Letters Patent

The subscriber, known to me as John Francis Chapman, and making part of the same containing a description in the words of the said John Francis Chapman himself of his machine for spinning flax & hemp.

This machine is a system composed of five wooden rollers, and one iron fluted cylinder in front of the machine. This cylinder is $3\frac{1}{8}$ inch diameter and receives pressure from a wooden roller of from 7 to 8 inches diameter covered with leather in order to give it more elasticity at each end of this upper roller is a lever 3 feet long at the end of which is fixed a weight of from 25 to 30 lbs. The five wooden rollers that are fixed on the same, principle one after the other at a distance of about 9 inches, are each pressed by another wooden roller on each side of which hangs a weight to give more pressure on the roller to combine the fibers of flax. These weights are of about 4 lbs. The first wooden roller is $3\frac{1}{8}$ inch diameter, the 2 of $3\frac{1}{12}$, the 3 of 3, the 4 of $2\frac{9}{12}$, the 5 of $2\frac{10}{12}$ inches. This difference exists in order that each cylinder may have some draft on the roll for the purpose of keeping the material always well extended.

These rollers turn by means of a bevel wheel fixed at the end of each, and receiving their motion from other wheels fixed on a shaft that receives its motion from a communication wheel turning with a pinion situated on a shaft of the iron fluted cylinder. The flax that passes, between the 5 wooden rollers, weighs 15 cwt, taking an extent of 12 feet 6 inches. The iron fluted cylinder situated in front of the machine moves 15 times quicker than the 5 wooden rollers by which means the flax passing through the cylinder is 15 times thinner.

This operation is necessary because the flax entering the machine comes out of a box of 30 feet long placed behind the machine. This box is about 3 inches wide and of a sufficient height to contain the mass of flax that weighs 15 cwt, in an extent of 12 feet six inches. On each side of this box is a board of the

same length, on which is arranged the whole length each number of flax which is turned in the box each time the iron fluted cylinder has turned 15 times, when the machine stops of itself by means of catch fixed on the first wooden roller, which catch holds a small lever that lets go a spring that corresponds with the moving shape. Thus each time the machine stops, an ounce of flax is put in another by this means; the box always contains the same quantity of material.

It is clear that the flax is spread out on the boards and which is turned in the box is very imperfect, and that the machine is reducing it 15 times thinner, it is deflected and irregularities are 15 times more imperceptible; consequently the ribbon is not being thereby produced is already 15 times more perfect, what makes this machine as well as the 2° & 3° preparations equally adapted for preparing hemp is that the 5 wooden rollers are at different places nearer or farther from each other by preparing hemp they are placed farther and for flax nearer to each other, and in such a manner that between the centre of the iron fluted cylinder, and the centre of the second wooden roller there is a distance equal to the length of the material employed. The distances of the rollers are indifferent. The first wooden roller has no weight for purposes, it serves merely to press by its weight those fibres of flax that are shorter than the generality of the others. Between the iron fluted cylinder and the first wooden roller is a conductor of iron plate that serves to prevent any fibres of the flax from separating as passing alongside the large wooden roller, pressing on the iron fluted cylinder. The flax falling out of the cylinder falls in a box which is removed and replaced by another when full.

Second preparation. The preparation of the same substance is the first, the measures of the different parts comprising it are absolutely the same as the first. The only difference is that for this second preparation there is no box placed behind but instead of that a number of ten boxes containing each enough of the first preparation. This number depends on the desired fineness of the yarn also on the qua-

by of the frame. The more there is put behind the machine the bigger will be the webbing coming out of it. In this machine a double set of rollers is employed that is to say there are two rollers or cylinders on the same shaft whereas on the first there is but one. All the coil is absolutely the same. The use of this second preparation is to improve the defects the first preparation has left. The webbing coming out of this preparation is 10 times more perfect than that coming out of the first.

Third Preparation. This preparation is equal in construction to the 2° except that on each end of the iron fluted cylinder there is a spindle and spool on which the material coming out of the cylinder twists itself so that it can be placed under the spinning frame. These two spindles turn by means of drawns fixed on the lower part in the middle of the frame and that turn in the same, by means of a pulley situated on the shaft of the iron fluted cylinder for spinning 11¹/₂ I. D. 3¹/₂ H. The twist ought to be one turn to 2 inches, or 6 turns to a foot. This third preparation is however supplied by a number of intubs containing webbing, coming out of the 2° preparation. The use of this 3° preparation is not only to give the material a last preparation but is also necessary to twist the webbing.

Spinning Machine. This machine has spindles on each side on the left there turns one placed the spools with the preparation twist from the third preparation, each twist passes between two cylinders of one inch and a wooden roller of 8 or 8¹/₂ inches thick situated under said spools and passes on each other by means of a hook drawn by a spring from these the twist passes and passes between two other wooden rollers, having no other pressure on each other than the proper weight of the upper roller. These two rollers serve merely to guide the twist over a small iron conductor which is placed between these rollers, and are two cylinders with copper rollers of two inches diameter on which passes a wooden roller that serves to punch the twist.

local that comes out of the iron conductor. This conductor is held
between by means of a hook drawn by a strong hand on the
frame. From this upper roller, the flat yam on the spindles situated
below them and that twist it to yam.

The wooden rollers situated above the conductor move a little quicker
than the upper iron cylinder in order to keep the twist always extended.
The iron cylinder with copper rollers delivers thirty times quicker than
the iron upper cylinder, by which means the yam gets 30 times finer
than the twist placed on the machine. By this means, if there was
yet any unevenness in the preparation it could be found 30 times more
insuperable in the yam and 30 times more perfect. Under the cyl-
inder with copper rollers is a box containing water, the copper rollers,
dipping in this water, get wetted, and turning wet the yam also.

To obtain the different numbers of yam the preparation must
be made coarse or fine, on which according the same proportion is to
give to the cylinder with copper rollers, more or less quickness in the iron
upper cylinder. (Disposition of the wheels.) At the end of the
machine is a shaft bearing a pulley on which is the moving shaft; at
the other end is a pinion of 30 teeth that turns each row of cylinders
with copper rollers which each of them have at their end a wheel of
100 teeth. as those wheels of 100 teeth are to run from the pinion of
30 teeth to catch in one another it is necessary to place between the pin-
ion and the wheel of 100 teeth a communication wheel of which the
number of teeth is indifferent, but one of 100 teeth is convenient to
to fill the space. At the opposite end there are two wheels instead of
one in order that the cylinder situated on this side may turn the same
way with the opposite cylinder. By this means the cylinders with
copper rollers receive their motion. At the end of the machine oppo-
site to the two mentioned wheels, and on the shaft of the last cylinder
as well copper rollers is a pinion of twenty teeth (the pinion of
20 teeth serves to give 30 the others) moving with a communication
wheel of 60 teeth—on this wheel of 60 teeth, placed another pin-
ion of 30 teeth moving with a great communication wheel of 93.2 teeth

2210x

(The diameter of this wheel is well proportioned for the space existing between cylinder with copper rollers and the upper iron cylinder a wheel of 232 teeth is best adapted.) This wheel of 232 teeth is a wheel of 100 teeth fixed on the upper iron cylinder and situated on the side of the machine opposite that where the moving pinion of 26 teeth is fixed, whilst a wheel of 16 teeth turns the upper iron cylinder. The same communication wheel of 100 teeth turns the upper iron cylinder on the other side by means of a communication wheel of 36 teeth placed between the wheel of 26 teeth and the wheel of 100 teeth fixed on the upper iron cylinder.

It will be easily observed that on one side of the wheel of 232 teeth, and immediate with the wheel of 100 teeth and that on the opposite side there is a communication wheel. This, in order to give to the two upper iron cylinders similar motion. The hand that makes the great board rise or lower receives its motion from the upper iron cylinder situated on the side of the machine. Whereas, is fixed the first moving shaft. The spindles move by way of 3 drums, that have their motion from a pulley situated on a vertical shaft which is perpendicularly fixed under the first moving shaft.

This last shaft has a bevel wheel of 150 teeth moving another bevel wheel of 50 teeth situated on the vertical shaft which bears the pulley that moves the drums, according to the hand it is intended to give to the yarn. One of these last bevel wheels must be changed in order to give more or less quickness to the spindles. The machine contains 6 spindles, 30 on each side.

This machine can either spin flax or hemp by means of placing the upper iron cylinder at a greater or less distance from the cylinder with copper rollers, which is done by moving the rollers of the upper iron cylinder higher or lower. These rollers running in a groove near in each of the supports of the upper part of the machine.

Witness,
